UNITED STATES PATENT OFFICE.

FRANCIS J. LAPOINTE, OF ANN ARBOR, MICHIGAN.

ADJUSTABLE FINISHING END FOR BROACHES.

Application filed August 16, 1927. Serial No. 213,312.

This invention relates to broaches and has for its object the provision of a finishing end for said broaches which may be adjusted so that its cutting edges will extend beyond the peripheries of the main broach cutters and cause the hole being broached to have the exact diameter required.

This object is attained by the device illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings:

Figure 1 represents a side elevation of a portion of a broach showing in section thereon an adjustable and expandable finishing member embodying the principles of the present invention.

Figure 2 represents a side elevation of the same in connection with a hole in material being broached and the finishing member slightly expanded.

Figure 3 represents an end elevation of the same.

Figure 4 represents an elevation of the outer end of the expandable finishing member, and

Figure 5 represents an elevation of the inner end thereof.

Similar characters indicate like parts throughout the several figures of the drawings.

In the drawings 10 is a portion of a broach provided with a plurality of annular cutters 11, 11^x which are separated from each other with their front faces 12 preferably nearly perpendicular to the axis of the broach but slightly undercut.

The peripheries of the cutters 11 are backed off slightly from the front faces 12 and at the rear of each cutter is a shoulder 13 which is parallel with the front face 11 so that the peripheral surface of each cutter is of equal width throughout and remains of equal width even after grinding.

Each cutter 11 has a diameter slightly greater than the cutter in advance thereof.

After the last cutter 11 has passed through the work it is necessary to finish and smooth the hole being broached and this is usually accomplished by a plurality of additional cutters 11^x formed upon the finishing end 60 of the broach.

In some classes of work this is all that is necessary to attain satisfactory results.

In many other classes of work, however, it is essential that the broach must be capable of cutting a hole very accurately, in many cases the demand being that the hole must not vary more than one ten thousandths of an inch.

Now if a hole is required to be finished to a size of say 1.2501 inches, the manufacturer of the broach must judge by previous experience just how many ten thousandths of an inch larger the broach must be made to compensate for the spring of the metal and 75 still make the hole of the required size.

All sorts of material are operated upon, that is, bar stock, forgings, castings, etc., none of which are of the same degree of hardness, and consequently the broach will 80 cut freer in one lot of material than in other lots of material.

The result is that in many cases the piece of material being broached will not pass inspection and this is a consequent loss both in 85 labor and material.

It is obvious, therefore, that it is most desirable to provide each broach with some means on its finishing end which may be expanded so that it may be set to within one 90 ten thousandths of an inch of the size of the hole required.

This requirement is fully met by the construction of broach herein shown and described.

In my improved broach the finishing end thereof is provided with an axially disposed tapered extension 14, the wall of which has an inclination of substantially one half inch per foot.

From the outer end of this tapered extension 14 projects the threaded shank 15 on which is mounted a nut 16.

Surrounding the tapered extension 14 is an adjustable finishing shell 17 consisting of 105 a helically wound strip of material 17^x the winds of which are normally in contact as shown in the drawings.

Under normal conditions the inner end of the shell 17 is spaced from the shoulder 18 11^x at the end of the body of the broach.

The strip 17* of the shell 17 preferably has a continuous cutting tooth 19 formed thereon which has a front face 20 nearly perpendicular to the axis of the broach, but the shell 17 may have annular teeth thereon if desired.

The periphery of the tooth 19 is backed off from the front face 20 and has a groove 21 in the rear thereof to receive the chips formed when the broach is being used.

10 By rotating the nut 16 the shell 17 may be forced toward the shoulder 18 and by so doing the shell is expanded to increase the diameter of the helically wound tooth 19.

By this means it is quite an easy matter 15 to make sufficient adjustment to allow for any differences in metal or in slight wear of the preceding sizing cutters 11*, it being understood that on the finishing end of the body of the broach 10, there are usually a 20 plurality of cutters 11* which are left full size.

When the shell 17 is placed upon the tapered extension 14 the diameter of the 25 helically disposed cutting tooth 19 is also full size or the same diameter as that of the sizing cutters 11*.

If the operator discovers that the broached hole is one or two ten thousandths of an inch too small in diameter, all that he needs to do is to turn the nut 16 slightly thereby 30 expanding the shell 17, broach a piece of material and calibrate it, repeating the operation until the shell 17 is expanded sufficiently to broach the size of hole required.

By means of this broach with its adjustable shell 17 not only may the differences in 35 the material being broached be taken care of but it also provides means whereby the variation in size of the broach due to wear may be compensated for.

40 This is of great importance as by providing the broach with the adjustable and expandable shell 17 the purchaser of the broach is able to obtain anywhere from eight to ten times the life out of the tool than could be obtained from a solid broach performing the 45 same operations.

It has been found by actual practice that the shell 17 may be expanded as much as .012 of an inch which is twice the expansion 50 ever required when the broach is in actual use.

It is believed that the operation and many advantages of the invention will be understood readily without further description.

55 Having thus described my invention, I claim:

1. A broach provided with a reduced tapered end with an unbroken peripheral surface; a helical member fitted to said 60 tapered end and having an outwardly extending undercut cutting tooth following

each wind thereof, said member being shorter than said tapered end; and means adjustable on said broach for forcing said member endwise on said tapered end and expanding it for its entire length.

2. A broach provided with a reduced tapered end with an unbroken peripheral surface; a helical member fitted to said tapered end and having an outwardly extending undercut cutting tooth following each wind thereof, said member being shorter than said tapered end; and means adjustable on said broach for forcing said member endwise on said tapered end and increasing the diameter of the cutting tooth throughout the entire length of said member.

3. A broach having a plurality of peripheral cutters and provided with a reduced tapered end with an unbroken peripheral surface; a member fitted to said tapered end and consisting of a helically wound strip with a continuous tooth following the winds thereof, said member being shorter than said tapered end with one end extending beyond the extremity of said tapered end; and adjustable means coacting with said outer end for forcing said member endwise and expanding said member from end to end with the periphery of said tooth beyond the peripheries of said cutters.

4. A broach having a plurality of peripheral cutters integral therewith and provided with a tapered end with an unbroken peripheral surface; a removable helically wound member fitted to and movable endwise of said tapered end, one end of said member extending beyond the extremity of said tapered end and said member having a continuous cutting tooth following the winds thereof; and means coacting with the outer end of said helically wound member for forcing it toward the larger end of said tapered end and expanding said member equally from end to end.

5. A broach having a plurality of peripheral cutters integral therewith and provided with a tapered end with an unbroken peripheral surface and a threaded shank extending therefrom; a removable helically wound member fitted to and movable endwise of said tapered end and having a continuous tooth following the winds thereof; and a nut on said shank coacting with one end of said member for forcing it endwise of the tapered end and expanding said member equally from end to end and increase the diameter of the periphery of said tooth.

Signed by me at Ann Arbor, Michigan, this 10th day of August, 1927.

FRANCIS J. LAPOINTE.
